(57) **CLAIM**

The ornamental design for a body part of electric grinder as shown and described.

DESCRIPTION

1. Body part of electric grinder

1.1 : Perspective

1.2 : Front

1.3 : Back

1.4 : Top

1.5 : Bottom

1.6 : Left

1.7 : Right

The body of an electric grinder, which is used to grind objects into fine particles or powder.

The broken lines show portions of the body part of electric grinder that form no part of the claimed design.
